Primary Examiner—Sandra L. Morris*Attorney, Agent, or Firm*—Oliff & Berridge, PLC[57] **CLAIM**

The ornamental design for work machine for power shovel,
as shown and described.

DESCRIPTION

FIG. 1 is a front view of a first embodiment of a work machine for power shovel;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a right side view of the first embodiment of the work machine for power shovel, also illustrating a bucket and dozer mounted as exemplary front attachments to the front of the work machine for power shovel. However, the design details of the bucket and dozer of FIG. 7 are hereby disclaimed and form no part of the claimed design;

FIG. 8 is a front view of a second embodiment of a work machine for power shovel, which includes a canopy mounted on the work machine for power shovel of the first embodiment, and which includes front, right side and left side guardrails and right and left side panels mounted on the work machine machine for power shovel of the first embodiment;

FIG. 9 is a rear view thereof;

FIG. 10 is a top view thereof, the bottom view being the same as FIG. 4;

FIG. 11 is a left side view thereof;

FIG. 12 is a right side view thereof; and,

FIG. 13 is a right side view of the work machine for power shovel of the second embodiment, also illustrating a bucket and dozer mounted as exemplary front attachments to the front of the work machine for power shovel. However, the design details of the bucket and dozer of FIG. 13 are hereby disclaimed and form no part of the claimed design.
